UNITED STATES PATENT OFFICE.

GEORGE H. RICHTER, OF BOSTON, MASSACHUSETTS.

DOCUMENT-FILE.

SPECIFICATION forming part of Letters Patent No. 712,596, dated November 4, 1902.

Application filed May 19, 1897. Serial No. 637,231. (No model.)

To all whom it may concern:

Be it known that I, GEORGE H. RICHTER, of Boston, county of Suffolk, State of Massachusetts, have invented an Improvement in 5 Document-Files, of which the following description, in connection with the accompanying drawings, is a specification, like letters on the drawings representing like parts.

This invention has for its object the production of an improved document-file which may be easily and quickly adjusted to securely hold any desired documents or papers.

In this my invention the back board or movable follower of the file is provided at its 15 outer side at some distance from its lower end with a stand on which is pivoted near its upper end a lever which constitutes a locking-brace and a stop, the lower end of said lever resting on a suitable track fixed with relation 20 to the bottom plate of the file and forming a brace to hold the follower up against the documents or papers when closed. Preferably this foot embraces and slides on the edges of the track referred to, while the lower end of 25 the lever rides on said track. The track is so constructed that the follower, with its attached foot, may be withdrawn from the front of the file until the foot reaches the end of said track, where the track is preferably cut 30 away somewhat or notched, and then by tipping the top of the follower toward the front of the file the foot of the follower may be readily detached from the track and the follower be removed from the file. The foot 35 and the lever are so constructed and combined that while the lugs of the foot engage the under edges of the track the lower free end of the lever, separately movable with relation to said foot and its lugs, rests on the 40 top of the track. By making the lever movable independently of the foot it is possible by merely bearing a little on said lever to tip the follower away from the foot without sliding the foot on the track, and when said lever is released its free end will drop onto the 45 track by gravity and will lock and brace the follower in position, and so, also, this separation of the free end of the lever from the foot enables the said lever to act automatic- 50 ally when the rear end of the file is raised,

the follower and lever descending by gravity, causing the lever to lock the follower in position against the papers in the file. The upper end of the lever by its contact with the stand near its pivotal point restricts the extent of movement of the lower end of said lever independently of the foot, and consequently limits the extent of backward-tipping movement of the follower. The lugs of the foot are shown as carried forward so as 60 to occupy a position well under the end of the follower toward the front of the file, as thereby the strength of the grip of the foot and the lever on the track may be greatly increased, and the harder the free lower end of 65 the lever is borne toward the track and the follower the greater the compression of the follower on the contents of the file, and owing to the described location of the lugs the follower is held firmly and securely, so that 70 it cannot tip backwardly. The lever hinged at its upper end to the follower is provided with a finger-loop, and the construction of the lever and the metal in the walls of the loop are of such character and thickness that 75 in case the lower end of the lever wears by contact with the track the loop may be somewhat compressed diametrically, thereby elongating the lever sufficiently to compensate for 80 the wear referred to.

Figure 1, in side elevation, represents a document-file embodying my invention; Fig. 2, a longitudinal section of the same, the dotted lines showing the gravitating lever or locking-brace lifted from the track. Fig. 3 85 is a section of Fig. 2 in the line x. Fig. 4 shows a portion of the bottom plate of the file. Fig. 5 is an enlarged view of the foot with its lugs, and Figs. 6 and 7 are modifications to be described.

The front A of the file, provided with a handle A', has about its inner side a flange a.

The bottom plate B of the file is composed of sheet metal bent or corrugated longitudinally to leave near the center of the plate 95 two grooves b, with a raised projection b' between said grooves, and at b² the said bottom plate is depressed to form rests to contact with the shelf on which the file sets, and the extreme side edges of the plate are upturned, 100

as at b^3 , to constitute side edges for the bottom plate of the file. The outer end of the bottom plate is provided with two sets of ears, as b^4 b^5 , the ears b^4 being at the ends of the 5 extreme bottom and those b^5 being at the ends of the side pieces, said ears being curled about a horizontal portion c of a wire C , while the ears b^5 are curled about and made to embrace an upright portion C' of said wire, the 10 extreme ends of said wire being attached by rivets a^3 to the flange a . The raised projection b' has suitably attached to it a track d , the side edges of said track being extended 15 over the grooves b in the bottom plate.

15 The follower E has suitably attached to it a stand e , which receives a pivot e' , which serves to pivotally connect the lever e^2 to said stand, the lower end of said lever being shaped 20 to present a substantially narrow rest e^3 to bear upon the surface or upper side of the track d , said lever having at its upper end, at or near its pivotal point, a stop e^4 , the lower end of the finger being provided with a finger-loop e^5 , the thickness of the metal in the 25 finger-loop being such that by a blow upon the finger-loop it may be somewhat compressed diametrically, thus elongating the effective length of the said lever sufficient to compensate for any wear between the end e^3 30 of the lever and the track. Projecting from the lower end of the follower at a point below the pivotal point of the lever e^2 is a foot f , (shown enlarged and detached in Fig. 5,) said foot having lugs f' , the shape of the foot being 35 such that the lugs are carried well forward under the lower end of the follower, the said follower when the foot is tipped well forward being introduced into the grooves b through the notches d^2 at the outer end of the 40 track, the lugs extending under the edges of the track, and after the lugs are under the edges of the track the follower is turned up and carried forward until the lower end of the lever e^2 rests on the top of the track.

45 The operator may engage the lower end of the lever e^2 and drawing upon it may pull the follower to the end of the track, and the follower will remain there in a position inclined away from the front; but to detach 50 the follower it will be tipped well over toward the front of the file, when the lugs will be in such a condition that they may be withdrawn through the notches, before referred to, thus removing the follower.

55 After documents have been placed in the file the follower may be placed by hand snugly up against the documents, and the free end of the lever following on the track will lock and retain the follower in the position in which 60 it may be left, the gravity of the lever causing it to act automatically, and the harder the lower end of the lever is pressed toward the foot while its lugs extend underneath the follower and embrace the lower edges of the 65 track the greater will be the compression of

the follower onto the documents and the more firmly will the follower be locked against any liability to wabble or vibrate. Preferably the stand and the foot will be cast together in one integral piece.

70 In the modification Fig. 6 the bottom plate B' is shown as provided with a central groove, and the foot f^2 is inserted in said groove, with the lugs f^3 extended well forward under the lower end of the follower and under 75 the edges of the track, the track in this modification being shown as a part of the bottom plate—viz., that part overhanging the groove—the lower end e^3 of the lever in such modification being broad enough to span the 80 space leading into the said groove of the bottom plate.

I prefer to use the foot represented in Figs. 3 and 5, it embracing the track; but the advantages herein referred to, due to separating the lever from the foot, so that each may be moved independently of the other, may be gained by a foot such as represented in the modification Figs. 6 and 7. So this invention is not limited to the particular shape of the 90 foot so long as it has ears which engage and ride on or in contact with a track, leaving the lever bearing on the top of the track or the top of the bottom plate free to be moved independently of the foot to lock the follower or compress it firmly against the documents in the 95 file.

In this file documents may be inserted while the follower is tipped back to the right, viewing Fig. 2, and then by engaging the handle 100 A' and elevating the right-hand end of the file the follower will fall by gravity and the lever e^2 will follow it, and acting by gravity it will effectually lock the follower in position to retain the documents in place.

105 Having described my invention, what I claim as new, and desire to secure by Letters Patent, is—

1. In a metallic document-file, a metallic bottom plate centrally bent longitudinally to form a plurality of grooves with a central raised portion therebetween, a longitudinal strip or track secured to the said central raised portion and extended laterally over the grooves at each side thereof, a carrier or follower having a stand fixed thereto and provided with a foot, a lever pivoted to said stand and provided at its lower end with a narrow rest, as e^3 , to bear upon the upper surface of the longitudinal strip or track.

110 2. In a metallic document-file, a metallic bottom plate centrally bent longitudinally to form a plurality of grooves with a central raised portion therebetween, said metallic bottom plate being also bent to form longitudinal 115 side rests on which the file sets and having the side portions of said bottom plate upturned to constitute the side edges for the file, the outer ends of the bottom plate and said side edges being also bent to form ears, a wire secured 120

at one end to the front of the file and embraced by the ears of the bottom and side edges, a follower, and a pivoted lever having a rest to bear upon the raised central portion 5 of the bottom plate to hold the follower in position.

In testimony whereof I have signed my

name to this specification in the presence of two subscribing witnesses.

GEORGE H. RICHTER.
